DESIGN FOR A VISE

Donald Ross, Middlesex, England

Application July 16, 1945, Serial No. 120,741

Term of patent 7 years

(Cl. D54—14)

To all whom it may concern:

Be it known that I, Donald Ross, a subject of the King of Great Britain and Ireland, residing at Middlesex, England, have invented a new, original, and ornamental Design for a Vise, of which the following is a specification, reference being had to the accompanying drawing, forming part thereof.

Figure 1 is an inverted plan view,
Figure 2 is a side elevation,
Figure 3 is an end elevation, and
Figure 4 is a perspective view of a vise showing my new design.

I claim:

The ornamental design for a vise, as shown.
DONALD ROSS.
